ANTENNA

William Sichak, Lyndhurst, N. J., assignor, by
mesne assignments, to the United States of
America as represented by the Secretary of War

Application April 30, 1946, Serial No. 665,936

5 Claims. (Cl. 250—33.65)

1

This invention relates to antennas for high frequency communication systems including radio object-locating (radar) systems and more particularly to a means for illuminating a beam-forming or beam-directing reflector.

In certain radar systems, for example, ground search apparatus or airborne search systems, it is desirable that the antenna produce a pencil-type beam which is characteristically narrow in one or both of the azimuthal or elevational planes. This has been accomplished by feeding the radiant energy into a pill-box type reflector which in turn feeds energy to and illuminates a secondary reflector. A pill-box reflecting element generally comprises a parabolic cylindrical reflecting surface, of small axial dimension, mounted between plane parallel metallic walls or plates which serve to enclose the ends of the parabolic cylinder. The radiant energy is fed into the pill-box by means of an enclosed transmission line such as a waveguide, if desired with a horn type termination, opening into the pill-box. Heretofore, the end of the transmission line or the horn termination has been located at the approximate focal point of the parabolic reflecting surface and within the pill-box itself. A pill-box reflecting surface is particularly suitable for illuminating a parabolic cylindrical reflector as it gathers the radiant energy into a primary beam of substantially uniform width in the horizontal plane, that is, a beam which is relatively wide in the horizontal plane and narrow in the vertical plane (when the pill-box is oriented with the axis of the pill-box cylinder vertical). This energy is directed onto the secondary reflector which may be of any desired configuration for producing any desired radiation pattern including one having a $csc^2 \theta$ configuration. While an antenna having such an arrangement has proved generally satisfactory, considerable difficulty has been experienced with pressurizing the feed within the pill-box and in matching the impedances so as to prevent unwanted reflections of energy from the pill-box back into the feedline.

It is one of the objects of the present invention to provide an antenna having a pill-box type primary reflector for directing radiant energy onto a secondary reflector in which the antenna components are so arranged that the difficulties heretofore encountered in such an arrangement are eliminated.

It is another object of the invention to provide an antenna having a horn feeding energy to a pill-box which in turn reflects energy in a flat beam pattern onto a secondary reflector shaped

2

to produce a radiation pattern of $csc^2 \theta$ configuration in which the feed and pill-box are so located as to facilitate pressurizing and impedance matching of the feed.

For a better understanding of the invention together with other and further objects thereof, reference is had to the following description of the invention taken in connection with the accompanying drawing, in which:

10 Fig. 1 is a simplified perspective view of the antenna, according to one embodiment of the present invention; and

Fig. 2 is a side sectional view of the same.

Fig. 2a is a side sectional view showing a modification of one element of the present invention.

Fig. 2b is a side sectional view showing a modification of another element of the present invention.

In the drawing, the antenna 10 is shown in simplified form and comprises a feeding transmission line which may be in the form of a rectangular waveguide 11, a pill-box type primary reflector 12 and a secondary or beam-shaping reflector 13. In the position as shown, the antenna 10 is adapted to be supported from the under surface of an aircraft and to direct the radiation pattern ahead (to the right) of secondary reflector 13 and downwardly towards the earth's surface. It will be understood, however, that while the present description is particularly directed to the antenna in the position indicated for airborne use, it may be reversed in position for use on ground equipment.

The pill-box type primary reflector 12 comprises a parabolic cylindrical reflecting surface 14 of small axial dimension, the axis being oriented vertically. Preferably the planes of the opposite ends of parabolic cylinder 14 are parallel. A metallic plate or sheet may be mounted 35 in the planes at one or both ends of parabolic cylinder 14, which planes serve to enclose the ends thereof. Thus, in the position shown in the drawing, a bottom plate 15 may be mounted to enclose the bottom end of cylinder 14 and a top plate 16 serves to enclose the upper end thus affording a substantially rectangular mouth or aperture 17. In accordance with the invention, top plate 16 extends away from reflecting surface 14 and beyond aperture 17 as a continuous 45 plane surface. If desired, bottom plate 15 may be omitted, so that the parabolic cylinder is closed at its upper end by top plate 16 only, without appreciably affecting the primary radiation pattern.

55 Energy is fed from a source (not shown) to

3

pill-box 12 by means of an enclosed transmission line which as shown is preferably in the form of a waveguide 11 having a rectangular shape in cross-section. Waveguide 11 extends through a suitable aperture 18 in top plate 16 and is then bent toward pill-box 12 so that the plane of its mouth 19 at the free end thereof is substantially perpendicular to the top plate 16 and spaced from and in parallel relation to the plane of aperture 17. Thus, the mouth of waveguide 11, which may be in the form of a flared horn having mouth 19a, shown in Fig. 2a, is located outside of pill-box 12, instead of entering the aperture 17 thereof in the manner heretofore utilized, while being at the approximate focal point of parabolic cylindrical surface 14. Inasmuch as the metallic top plate 16 itself acts as part of mouth 19 or horn mouth 19a and is thus effective to shape the primary pattern of energy issuing from mouth 19 or horn mouth 19a onto the parabolic surface 14, mouth 19 or horn mouth 19a may be of relatively small dimensions.

Secondary reflector 13 may be shaped to produce any desired beam pattern by reflecting energy directed thereon by pill-box 12. It is often desirable that the energy distribution in a vertical plane be such that the variation of energy density versus the radiation angle approximates a cosecant-squared function. This distribution provides generally uniform echo strength for targets disposed at substantially equal elevations with respect to the antenna regardless of whether the target is close in or distant. Thus, secondary reflector 13 preferably comprises a portion of a generally cylindrical reflector having its reflecting surface 13' shaped according to geometric optics to produce a radiation pattern closely approximating the relation $csc^2 \theta$ in elevation, where θ is the radiation angle measured from the axis of an undistorted or symmetrical beam pattern, i. e., a pattern normally produced by an undistorted or conventionally shaped reflector. Reflecting surface 13' may therefore comprise a portion formed as a parabolic surface for directing the energy beam along a main path with another portion (as shown the upper portion) having a modified non-parabolic shape adapted to direct a component of the energy along a divergent path whereby an unsymmetrical radiation pattern which generally varies as the square of the cosecant of the angle, measured from the axis of the radiation pattern emanating from pill-box 12, is produced.

Reflector 13 is preferably located so that its focal line, i. e., the locus of its focal points, normally lies in a horizontal plane preferably also lying substantially in the plane of the aperture 17 of pill-box 12. Thus, the energy reflected from parabolic surface 14, the pattern of which is generally wide in azimuth and narrow in elevation to give a substantially flat beam pattern substantially parallel to plate 16, is adapted to illuminate and be reflected from reflecting surface 13' in a radiation pattern which is substantially uniform in azimuth and which is of $csc^2 \theta$ configuration in elevation.

The top plate 16 preferably extends from pill-box 12 to reflector 13 and may actually be attached along the top edge 20 of reflector 13. Alternatively, the reflector 13 may approach close to the top edge 20 and be spaced slightly therefrom to permit reflector 13 to move relative thereto. For example, reflector 13 may be rotatable or tiltable about a horizontal axis, as shown in Fig. 2b, whereby the distribution pattern may be varied to obtain substantially uniform gain and

4

echo strength in the ground plane for different altitudes of the antenna when the latter is airborne. For satisfactory operation, the depth of reflector 13 that is the distance between the longitudinal edges thereof should be approximately twice the axial length of the pill-box 12.

With the antenna arrangement as hereinbefore described the plane of polarization of the radiant energy as it issues from the mouth 19 or horn mouth 19a of waveguide 11 is parallel to the top plate 16, as indicated by the arrows in Fig. 1, and there is a substantially zero electrical field along the metallic lower surface of plate 16. Consequently, very little power will be reflected back into mouth 19 or horn mouth 19a. Thus, with the present arrangement, it is very easy to match the horn to space and to the impedance and pill-box 12. Furthermore, as the waveguide feed or horn radiating element 11 is disposed outside of the pill-box 12, it may be easily pressurized according to well-known methods, such as by sealing with dielectric material to prevent the effects of variation of pressure and weather on the radiation of energy therefrom.

While there has been described what is at present considered an illustrative embodiment of the invention, it will be obvious to those skilled in the art that various changes and modifications may be made therein without departing from the invention.

What is claimed is:

1. An antenna for radar systems comprising a primary reflector having a symmetrical parabolic cylindrical concave reflecting surface terminated by a pair of edges substantially parallel to its focal line, a pair of plate members disposed with their planes substantially perpendicular to the focal line of said primary reflector and adjacent to the ends of said primary reflector, a rectangular waveguide having one end adapted to be connected to a source of electromagnetic energy and a plane open end positioned substantially parallel to the plane determined by said pair of edges to illuminate the reflecting surface of said primary reflector with said energy, said radiating end being located outside the space bounded by the reflecting surface of said primary reflector and the plane determined by said pair of edges, and a secondary reflector having a generally parabolic cylindrical reflecting surface positioned to be illuminated with energy from said primary reflector and at a greater distance from said primary reflector than said radiating end of said waveguide, said secondary reflector being disposed with its focal line parallel to the planes of said plate members, one of the edges of said secondary reflector being substantially in the plane of one of said plate members, said one plate member extending the distance between said primary reflector and to said secondary reflector.

2. An antenna according to claim 1 in which said plate member is spaced capacitively from said one edge of said secondary reflector and said secondary reflector is tiltable about its focal line.

3. An arrangement for illuminating a directive reflector comprising a parabolic cylindrical reflecting surface having a focal line, conductive end plates perpendicular to said focal line and adjacent to said reflecting surface, the terminations of said reflecting surface and one of said end plates being contiguous with each other to form a radiating aperture positioned intermediate said focal line and the vertex line of said reflecting surface, the other of said end plates being extended beyond said radiating aperture to a posi-

tion adjacent to the directive reflector to be illuminated, and means positioned on said focal line to illuminate said reflecting surface with polarized electromagnetic energy, said last-mentioned means being oriented to provide electromagnetic energy polarized parallel to said end plates.

4. An arrangement for illuminating a main directive reflector comprising a first directive reflecting surface having a focal line, at least one conductive end plate perpendicular to the focal line and adjacent to said first reflecting surface, the intersection of the terminations of said first reflecting surface and said end plate forming an aperture for radiating energy onto the main directive reflector, said focal line being outside of the space bounded by said aperture and said reflecting surface, said end plate being extended beyond said radiating aperture to a position adjacent the main directive reflector, and means positioned on said focal line for illuminating said first reflecting surface with polarized electromagnetic energy, said last-mentioned means being oriented to provide electromagnetic energy polarized parallel to said end plate.

5. A directive antenna with means for distorting the radiation pattern from said antenna into a $\csc^2 \theta$ pattern in one plane, where θ is the angle measured from the axis of directivity of the undistorted radiation pattern, comprising a first parabolic cylindrical reflecting surface having a first focal line, a second parabolic cylindrical reflecting surface having a second focal

line and mounted facing said first reflecting surface with said second focal line being skew relative to said first focal line and perpendicular to a line parallel to said first focal line, a conductive end plate mounted perpendicular to said first focal line and extending between said first and second reflecting surfaces with said second focal line adjacent said end plate and on the same side of said end plate as said reflecting surfaces, and radiating means positioned to illuminate said first reflecting surface.
